UNITED STATES PATENT OFFICE.

JAMES H. TAYLOR, OF TOLEDO, OHIO.

VACUUM-CLEANER.

1,157,456.

Specification of Letters Patent. Patented Oct. 19, 1915.

Application filed June 12, 1911. Serial No. 632,538.

To all whom it may concern:

Be it known that I, JAMES H. TAYLOR, a citizen of the United States, residing at Toledo, in the county of Lucas and State of Ohio, have invented certain new and useful Improvements in Vacuum-Cleaners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to a vacuum carpet cleaner, operated by hand after the fashion of a common carpet sweeper, and is designed to furnish a mechanism by which the exhaust fan is caused to rotate constantly in one direction by means of the to-and-fro motion of the machine upon the floor and gearing intermediate the supporting wheels of the machine and the fan.

20 My invention is also designed to furnish automatic devices for slightly tilting the mouth of the inlet nozzle at its advance side as it is moved forward and backward along the floor.

25 My invention also relates to certain details of construction hereinafter described and pointed out in the claims.

To this end my invention consists in the devices, construction and arrangement of parts hereinafter described, and shown and 30 illustrated in the accompanying drawings, in which,

Figure 1 is a side-elevation of a portion of one of the beveled gear-wheels hereinafter referred to; Fig. 2, a transverse sectional elevation of the same on line 2—2, Fig. 1; Fig. 3, a side elevation of my device, the fan and the fan-case being shown in central vertical section and one of the supporting wheels being removed and portions of the frame hereinafter referred to being broken away for the sake of clearness; Fig. 4, a front-elevation of my machine with a part thereof illustrated in central vertical section; Fig. 5, a side-elevation of a portion of another of the gear-wheels hereinafter referred to, and Fig. 6, a central sectional elevation of the same taken on line 6—6, Fig. 5.

Like parts are represented by corresponding numerals throughout the drawings.

55 In the drawings, 1 is a frame or housing consisting of a pair of disk-like plates 2—2

rigidly connected by cross-rods 3 and having formed therewith or secured thereto centrally, stub-shafts 4. Upon these two outwardly projecting shafts are journaled supporting drive-wheels 5, internally toothed, as at 6, and being, preferably, shod with stout rubber bands or tires 7. The internally toothed rims of the wheels are turned inwardly, their internal diameter being 60 slightly greater than the diameter of the disk-like portions 2 of the frame which are overlapped by the wheel-rims. Thus the stationary disks 2 form closures for the cavities of the wheels. The wheels are secured 65 against lateral displacement by means of headed bolts 8 passing through the hubs 4^a and provided at their threaded ends with nuts 9.

10 is a shaft journaled in the disks 2 near 75 their top and having fixed thereon at its ends pinions 11, which engage and are driven by the internal teeth of the wheels 5.

12—12 are beveled gears mounted loosely upon the shaft 10 and constantly in mesh 80 with a beveled pinion 13, loose upon vertical shaft 14, stepped at its bottom, as at 15, in a socket in the top of a pair of arched bars 16 springing from and supported by the cross-rods 3. At its upper end the shaft 14 85 has fixed thereon the exhaust fan 17 inclosed in casing 18. The case is supported and held in fixed relation to the frame of the machine by means of standards 19 bolted or screwed at top to the underside of the case and at bottom to the inner faces of the disks 2. In the underside of the casing, near its center, is an inlet opening 19 to which is connected a flexible inlet-tube 20 carrying at its bottom a nozzle-piece 21, of the usual or any preferred 95 construction, adapted and arranged to move with its downwardly turned mouth close to or against the floor. In the outer edge of the fan-casing is an opening 22 which is connected with one end of a dust-bag 23, the other end of which is secured to and supported by the handle of the machine.

It is evident that if the device be propelled upon its supporting wheels, the fan may be caused to revolve by means of the 105 gears intermediate the internal teeth of the wheels 5 and the fan. To be effective, the fan must be caused to rotate constantly in the same direction. This is accomplished by means of the devices now to be described.

Transversely through the shaft 10 are holes 24 in which slide loosely pins 25. In

the hubs of the beveled gears 12—respectively—are recesses 26 for the reception of the pins and in which the pins freely slide vertically in their bearings. The horizontal 5 walls of the cup-like recesses 26, against which the ends of the pins abut, are toothed, as at 27, the sides of the series of teeth being, in one direction, formed as shoulders or stops for the ends of the pins, the opposite 10 sides of the teeth being sloped or curved in wedge-like fashion so that when the end of the pin rides upon these inclined surfaces, no motion is transmitted from the shaft to the gear. The shoulders of the teeth 27 in 15 one of the gear-wheels 12 are disposed oppositely to the like shoulders of the companion gear-wheel 12, the arrangement being such that when the supporting wheels are propelled in one direction, causing the pinion 20 and shaft 10—11 to revolve, one of the pins 25 will drop into contact with the shouldered side of one of the teeth 27, causing the corresponding gear-wheel 12 to rotate and—through the beveled pinion 13—to communicate motion to the fan, and when the supporting 25 wheels are moved in the opposite direction, the motion of the shaft 10 is reversed so that now the pin 25 of the other beveled gear-wheel drops into engagement 30 with the shouldered side of the teeth 27, causing the gear-wheel to revolve while the other one stands idle. It will be seen that thus the two beveled gear-wheels 12, located at opposite sides of the beveled pinion 13, by 35 means of their clutch-pins alternately engage with the shaft 10, as the machine moves to and fro, causing the pinion 13 and the fan to rotate always in the same direction.

If the engagement of the pinion 13 with 40 its shaft were rigid, the shaft would, with its fan, cease to rotate at each pause of the machine in its movement to and fro, and thus the benefit of the momentum of the fan would be lost. To obviate this difficulty the 45 pinion 13 is loose upon its shaft and is supplied with a clutch which engages and causes the fan-shaft to turn in but one direction. The clutch consists of a sleeve 28 revoluble with but longitudinally movable upon the 50 vertical fan-shaft. The projecting ends of the pin 29 passing horizontally through the fan-shaft engages vertical slots in opposite sides of the sleeve 28, thus permitting the vertical movement of the sleeve while causing the shaft and sleeve to rotate together. The lower end of the sleeve 28 is notched to 55 form shoulders 30 which—when the sleeve is in its lowered position—engages corresponding shoulders 31 formed in the top of the pinion 13. The vertically meeting surfaces of the sleeve 28 and the pinion 13 are beveled, as at 32, so that when the fan and its shaft are revolving and when the pinion is 60 stationary the beveled surfaces of the sleeve 65 and pinion will, by their wedge-like action,

cause the sleeve to slide upwardly and out of engagement with the pinion so that the rotation of the fan is not interfered with by the pause in the forward and backward movement of the machine.

The handle 33 of the machine is pivoted to the top of a short lever 34 fulcrumed, as at 35, upon an extension of one of the arch-bars 16. At its lower end the lever is pivotally connected, as at 36, with a rod 37 which, at 75 its lower end, is pivoted, as at 38, to a ring 39 clamped upon the upper end of the nozzle-piece 21.

40 is a bar pivoted at one end, as at 41, upon the inner face of one of the frame-plates 2 and at its other end pivotally connected, as at 42, with the nozzle-piece 21 below the band 39. When the handle 33 is pressed forwardly the parts from 34 to 42 inclusive, cause the front part of the nozzle 85 to tilt slightly upwardly to permit ingress of air. When the handle of the machine is forced in the opposite direction the opposite effect takes place and the opposite side of the mouth piece of the nozzle, is, in like 90 manner, tilted slightly upwardly.

In the foregoing description I have explained and illustrated a cheap, simple and effective form of clutch for the shaft 10 and the beveled gear-wheels 12, as well as for the 95 fan-shaft and the pinion 13, but it should be understood that I do not limit my invention to these specific clutches as other kinds of clutches operating with the same effect will suggest themselves to those skilled in 100 the art.

Having described my invention, what I claim and desire to secure by Letters Patent, is,—

1. In a device of the described character, 105 in combination, a frame, supporting-wheels for the frame, a fan and a fan-casing mounted upon the frame, a shaft for the fan, gears connected with the supporting wheels, two 110 clutches in operative relation to the gears, arranged to positively drive the gearing during both the forward and backward movement of the mechanism, and a third clutch arranged to permit the fan to run independently of the gearing.

2. In a device of the described character, 115 in combination, a frame, a single pair of supporting-wheels journaled upon the frame, a fan and fan-casing mounted upon the frame, a shaft for the fan, a train of 120 gears—intermediate the supporting wheels and the shaft—adapted by the to-and-fro movement of the supporting wheels to rotate the shaft, a clutch-mechanism in said train of gears which communicates motion to the 125 fan in but one direction, and another clutch mechanism which permits the rotation of the fan in such direction independently of the train of gears.

3. In a device of the described character, 130

the combination of a frame, a pair of internally geared supporting wheels journaled upon the frame, a shaft journaled upon the frame, a pair of pinions fixed upon the shaft 5 and in operative engagement with said internal gears, a pair of opposed beveled gear-wheels loose upon said shaft, for each beveled gear-wheel a clutch which operatively engages the wheel with the shaft in but one 10 direction, a fan, a fan-shaft, a beveled pinion loose upon the fan-shaft and engaged at its opposite sides with the beveled gear-wheels, and a clutch which operatively engages the fan-shaft with the beveled pinion only in the 15 direction of the movement of the fan.

4. In a machine of the class described, the combination with a traction wheel for driving, suction producing mechanism adapted to be driven thereby, and driving means between said mechanism and said traction wheel; of clutch means operatively connecting said driving means and said traction wheel, and other clutch means operatively connecting said driving means and said suction producing mechanism.

5. In a machine of the class described, the combination with a traction wheel for driv-

ing, suction producing mechanism adapted to be driven thereby, and driving means between said mechanism and said traction wheel; of one-way clutch means operatively connecting said driving means and said traction wheel, and other one-way clutch mechanism operatively connecting said driving means and said suction producing mechanism, whereby rotation of said traction wheel in one direction disconnects said driving means.

6. In a machine of the character described, the combination with a traction wheel for driving, suction producing mechanism adapted to be driven thereby, and driving means between said mechanism and said traction wheel; of two one-way clutches, one interposed between said traction wheel and said driving means, and the other interposed between said driving means and said suction producing mechanism.

In testimony whereof I affix my signature in presence of two witnesses.
